UNITED STATES PATENT OFFICE.

JACOBS W. SCHUCKERS, OF PHILADELPHIA, PENNSYLVANIA.

TYPE-WRITING MACHINE.

SPECIFICATION forming part of Letters Patent No. 423,576, dated March 18, 1890.

Application filed September 21, 1886. Serial No. 214,147. (No model.)

To all whom it may concern:

Be it known that I, JACOBS W. SCHUCKERS, a resident of Philadelphia, in the county of Philadelphia and State of Pennsylvania, have 5 invented an Improved Type-Writing Machine, of which the following is a full, clear, and exact description, reference being made to the accompanying drawings.

This invention relates to a new construction 10 of the class of type-printing machines which are known as "type-writers" and "typographic machines," and has for its object to simplify the mechanism as compared with that of type-writers and typographic machines now in use, and to produce a perfect machine in a more economical and substantial manner than has heretofore been accomplished.

The invention consists, first, in the use of 20 an oscillating frame, which carries types for printing or imprinting, and which is combined with the actuating-keys in such manner that upon the depression of a key it will be moved into position to bring a certain desired type 25 in line with the impressing lever or rod.

It also consists in combining with the devices just mentioned a peculiar mechanism for feeding the paper and in other details of improvement, which will be hereinafter more 30 fully described.

In the accompanying drawings, Figure 1 is a plan or top view, partly in section, of a type-writer constructed according to my invention. Fig. 2 is a cross-section on the line *c c*, Fig. 1. 35 Fig. 3 is a longitudinal section on the line *k k*, Fig. 1. Fig. 4 is a longitudinal section on the line *c k*, Fig. 1. Fig. 5 is a detail top view showing the keys and the guide-plate for the same. Fig. 6 is a detail face view of one of the keys. 40 Fig. 7 is a face view of the spacing-key. Fig. 8 is a detail top view of part of the impressing lever or rod.

In the drawings, the letter A represents the case or framing of my machine. In the same 45 is pivoted on a suitable support at *a* a lever B, which is more clearly shown in top view, Fig. 1, as to its shape—that is to say, this lever has a preferably sector-shaped end on one side of the pivot *a* and a shank on the 50 other side of said pivot. The sector-shaped end of the lever B contains a grooved or slotted guideway *b*, which is by preference con-

centric with the axis of the pivot *a*. This guideway *b* serves to contain and support series of types or type-blocks C, there being 55 as many of these types within the guideway as the machine is intended to use. That one of these types which is brought into the line *k k*, Fig. 1, will be the type intended for printing, because beneath that line *k k* will be 60 found the impression lever or rod for crowding said type against the paper; hence the operation of the machine as far as described is to bring the types in the guideway *b* successively into alignment with the impression 65 rod or lever and to move the impression rod or lever against the type presented to it from time to time, so as thereby to produce the desired imprint.

Each type C is held in its normal position 70 in the guideway *b* by its own weight, or by a spring or springs *p* bearing upon or connecting with the body of said type, as indicated in Figs. 3 and 4.

D is the impression lever or rod, which is 75 adapted by means of its end *f* to come in line with one of the types C in the guideway *b*. The lever D is at *d* pivoted to the framing A.

Fig. 3 shows the lever D in its normal position, in which it is held by a spring *e* or 80 analogous means. Fig. 4 shows it in the act of moving the type which is aligned with it toward the paper-carrier E.

The keys F F for actuating the levers B and D have their shanks passed through a slotted 85 key-box G, which is supported by the frame or case A, and are of substantially the form shown in Fig. 6—that is to say, each key which is to be used for the moving of a type and for printing has an inclined slot *g*, which 90 straddles the shank of the lever B, (see Fig. 2,) and which, when the key F is pressed from the normal position in which it is held by a spring *h* (see Fig. 3) into the actuating position in which it is represented in Fig. 2, causes 95 the lever B to be swung sidewise in accordance with the extent of inclination of the slot *g*.

The keys F F of the machine, by reason of their varying distances from the pivot *a* of 100 the lever B and by variations in the inclinations of their slots *g*, will impart to the lever B varying degrees of motion, so that each key is adapted to bring one certain type into

alignment with the impression-lever. When all the keys F are untouched, as in Fig. 3, the lever B will be entirely clear of them; hence when one is pressed that key alone will move the lever B and bring the desired type C into alignment with the impression lever or rod D. The inner end of each key afterward presses on the lever D, as in Fig. 4, so as to cause it to push a type against the paper.

10 The inclined slots g in several of the keys F may not only vary in degree of inclination, but also in direction of inclination, (see the dotted lines in Fig. 6,) so that the guideway b may be moved by some keys in one direction and by others in the opposite direction, to enable all the different types to be conveniently brought into position for printing. Each of the keys F, moreover, has along its outer face an inclined edge i, which is for 15 the purpose of feeding the paper—that is to say, this inclined edge i, when the key is pressed, crowds a sliding or swinging bar H from the normal position shown in Fig. 1 into the position shown in Fig. 2. This sliding or 20 swinging bar H has a pawl j, which enters the teeth of a sliding rack I and pushes that rack ahead the desired distance whenever a key is pressed.

Keys intended to affect broad types—such 25 as print the letters "m" and "w" and the capital letters—will be adapted to move the bar H farther than keys that affect narrower types. Fig. 6 shows by dotted lines at the right-hand side how a key for moving the bar H farther 30 than that shown by full lines in the same figure will be constructed. The sliding rack I has also a row of teeth which gear into a toothed wheel l on a shaft J, so that whenever a key is pressed and the bar H moved, and 35 with it the pawl j and rack I, intermittent rotary motion will be imparted to the shaft J. This shaft by another gear-wheel m gears into another rack L, which carries a post M, or a series of posts, if desired, to which the 40 paper-carrying drum E is connected, so that whenever the rack L is moved the drum E will be moved in the same direction and to 45 the same extent.

It will be seen from the special construction 50 which is represented in the drawings that the rack I being above the wheel l, and the rack L being below the wheel m, these two racks will move in opposite directions; but this is a matter of convenience, and may be modified 55 in an operating-machine. After a key has done the work of moving the lever B, the rod H, and finally the impression-lever D, it is let

go by the operator, and will then by its spring h be moved back into its normal position, whereupon a spring n will slide or swing the 60 rod H back into its normal position, the spring e carrying the lever D back to its normal position, the lever B being carried back to its normal position, which is the position shown by full lines in Fig. 1 by the key last actuated, 65 as all the keys have the lower ends of their slots g in line with the shank of the lever B when that is in the normal position.

I have stated in speaking of the lever B that it has a shank. By this I mean that with 70 reference to one row of keys F it has a shank, which may be entirely straight or slightly curved or bent; but it is clear that two or more rows of keys may be employed on the same machine, in which case the lever B 75 would have a shank for every row of such keys.

The key F^x, which is represented in Fig. 7, is the spacing-key for the machine, having only the inclined portion i for moving the bar 80 H and sliding racks, but no means for moving the levers B and D, the slot q, which is in the key-box G for its reception, being at the side of the levers B and D. (See Fig. 5.)

The devices hereinabove described can be 85 used in a typographic machine, in which for the paper-carrying cylinder a matrix-carrier is substituted.

I claim—

1. The lever B, having slotted guideway b, 90 carrying types C, in combination with actuating-keys and with an impression rod or lever, substantially as specified.

2. The key F, constructed with inclined slot g, in combination with the lever B, carrying 95 the type C, substantially as specified.

3. The key F, constructed with the slot g and inclined edge i, in combination with the swinging type-carrying lever B and with the movable bar H, substantially as specified. 100

4. The combination of the key F, the type-carrying lever B, the feed-bar H, and the impression-lever D, all operated by said key, substantially as set forth.

5. The combination of the type-carrying lever B with the impression-lever D and actuating-key F, all arranged so that upon actuating the said key the type-carrying lever will first be moved and after that the impression-lever, substantially as specified. 105
